M. J. FORD.
HOSPITAL BED.
APPLICATION FILED JUNE 18, 1917.

1,246,078.

Patented Nov. 13, 1917.

Inventor

Michael J. Ford,

By *Hiram A. Sturges,*
Attorney

UNITED STATES PATENT OFFICE.

MICHAEL J. FORD, OF OMAHA, NEBRASKA.

HOSPITAL-BED.

1,246,078.

Specification of Letters Patent. Patented Nov. 13, 1917.

Application filed June 18, 1917. Serial No. 175,395.

To all whom it may concern:

Be it known that I, MICHAEL J. FORD, a citizen of the United States, residing at Omaha, in the county of Douglas and State of Nebraska, have invented certain new and useful Improvements in Hospital-Beds, of which the following is a specification.

This invention relates to an improvement in hospital beds, and has for its object to provide a bed for general use in hospitals or individual use, which will include new and useful features without adding materially to the cost of manufacture.

The invention consists of the novel construction, combination and arrangement of parts as described herein and claimed, and as illustrated in the accompanying drawing, it being understood that changes in form, size, proportion and minor details may be made as may be found to be of advantage and more particularly pointed out in the claims.

In the drawing, Figure 1 is a view in side elevation of a hospital bed embodying my invention, the douche-supporting standard being disposed horizontally. Fig. 2 is a transverse section on line 2—2 of Fig. 1, the douche-supporting standard being extended, and disposed vertically, a douche receptacle being added. Fig. 3 is a transverse section through the post and standard on line 3—3 of Fig. 2, the scale being enlarged. Fig. 4 is a detail relating to Fig. 3, showing a face view of a grooved alining block. Fig. 5 is a side view of a clip employed for supporting the standard in a horizontal position. Fig. 6 is a transverse section on line 6—6 of Fig. 5. Fig. 7 is a plan view of a towel rack employed.

40 Referring now to the drawing for a more particular description, the invention is illustrated in connection with the conventional head-piece 8 and foot-piece 9 of a bed and intermediate side rails. The usual racks 11
45 are employed for use in connection with the movable section 12 and props 13 for supporting a patient in an inclined position, certain other features being also used and not now specifically described, since they do
50 not relate to the present invention.

In order that liquid douches may be conveniently administered, and that the pressure of the liquid to determine the force of the flow for the douches, may be increased or diminished, as may be required, I provide a standard 14 which may be secured to one

of the posts 15 and may be disposed vertically for supporting a receptacle 16 at a suitable elevation, or may readily be disposed horizontally when not in use, as indicated by the broken lines in Fig. 2, said standard being provided with a slidable and adjustable extension 17 having a hook 18 near its free end for a support of the douche-receptacle, and preferably being provided with a ball 19 and a terminal projection 20.

The standard 14, preferably, has a less length than the foot piece 9, so that the parts, when disposed horizontally, will not 70
obtrude by projecting beyond the sides of the bed.

In order that the standard may be maintained in either a horizontal or vertical position, certain devices are employed which do not add appreciably to the cost of production, and may be conveniently applied and operated. Mounted on the tubular post 15 is a collar 21, and secured upon the collar is an alining-block 22 having its outer side provided with a vertical groove *a* intersected by a horizontal groove *b*, the degree of curvature of said grooves corresponding to the convexed surface of the tubular standard 14. 75 80 85

Numeral 23 indicates a suitable washer or contact-block, preferably having a flat outer surface, its inner wall being of concaved form, also conforming approximately to the convexed surface of the standard. All of the parts are apertured, as best shown in Fig. 3, for receiving a screw 24.

The screw has a threaded connection with the collar and post 15, and it will be understood that if the screw is rotated in one direction, the contact-block may be moved inwardly to press the standard against the alining-block in either of the grooves *a* or *b*, and if the screw is rotated in an opposite direction, the contact-block 23 may be moved outwardly to permit the standard to be swung substantially 90 degrees. 95 100

The douche-receptacle 16 is provided with a discharge-pipe 25 of an adequate length so that its contents may be applied or administered for all usual purposes or requirements, and by means of a set-screw 26 the extension-rod 17 may be elevated or lowered, so that the pressure of the liquid may be greater or less in degree, as may be required, this being a feature of importance. 110

When the douche is not in use the stand-

ard may be swung to a horizontal position and secured to the post 27 of the foot piece 9. A collar 28 is mounted on this post at substantially the same height as the collar 21, and is provided with an apertured bracket 29; and when the standard is swung downwardly to a horizontal position the extension 17 is moved outwardly a limited distance so that the projection 20 will enter the aperture of the bracket, and by use of the set-screw 26 any slidable movement of the extension with reference to the standard will be prevented, to maintain the projection in the aperture of the bracket, the ball 19 being in engagement with the post 27 to prevent vibration, the standard at this time being disposed in the horizontal groove *b* of the alining block 22, and firmly held therein by means of the screw 24.

20 Numeral 30 indicates a towel-rack which, preferably, is mounted on the posts and preferably has a length substantially equal to the width of the head piece 9.

Having fully described my invention, 25 what I claim and desire to secure by Letters Patent is,—

1. In a receptacle-supporting device for a bed frame, a standard, an alining-block mounted on the frame and provided with a 30 vertical groove and a horizontal groove, a contact-block provided with a groove, a bolt traversing the contact-block, the standard and alining block and having a threaded connection with the frame, said bolt being adapted to be rotated for pressing the 35 standard in the vertical groove of the alining-block for sustaining the standard in an upright position when the receptacle engages the standard, and adapted to be rotated for pressing the standard in the horizontal groove of said alining-block for sustaining the standard in a horizontal position when the receptacle has been removed therefrom.

45 2. In a receptacle-support for a bed frame, said frame being provided with a vertical groove and having a horizontal groove intersecting the vertical groove, a tubular, transversely apertured standard having a 50 transverse curvature conforming substantially to the transverse curvature of the grooves, a bolt engaging the frame and disposed in the transverse apertures of the standard and adapted to have a rotatable 55 movement for pressing the standard within the horizontal groove of the frame to sup-

port the standard in a horizontal position, and adapted to be rotated for pressing the standard within the vertical groove of the frame to maintain the standard in an upright position for supporting a receptacle thereon.

3. In a receptacle-support for a bed frame, said frame having a part provided with a bracket and having a part provided with a 60 vertical groove and a horizontal groove intersecting the vertical groove, a tubular, transversely apertured standard having a transverse curvature conforming substantially to the transverse curvature of the 65 grooves, a rod provided with a detent and mounted in the bore of the tubular standard, means to adjust the rod longitudinally of said standard, a bolt engaging the frame and disposed in the transverse apertures of 70 the standard and adapted to have a rotatable movement while the standard is engaging the bracket for maintaining the standard in a horizontal position, and adapted to have a rotatable movement for 75 pressing the standard within the vertical groove of the frame to maintain the standard and its rod in an upright position for supporting a receptacle on the detent of 80 said rod.

4. In a receptacle-support for a bed frame, said frame being provided with a vertical groove and having a horizontal groove intersecting the vertical groove, a cylindrical, 85 apertured standard having a transverse curvature conforming substantially to the curvature of the grooves, an apertured contact-piece having a concaved part, a bolt disposed in the apertures of the contact-piece and standard and adapted to have a revoluble movement for pressing the standard within the concaved part of the contact-piece and horizontal groove of the frame for supporting the standard in a horizontal 90 position, and adapted to have a revoluble movement for pressing the standard within the concaved part of the contact-piece and vertical groove of the frame to maintain the standard in an upright position for supporting a receptacle thereon.

100 In testimony whereof, I have affixed my signature in presence of two witnesses.

MICHAEL J. FORD.
